US00D937139S

(12) **United States Design Patent** (10) **Patent No.:** **US D937,139 S**
(45) **Date of Patent:** **** Nov. 30, 2021**

(54) **STROLLER**

(71) Applicant: **Thule Sweden AB**, Hillerstorp (SE)

(72) Inventors: **Henrik Eriksson**, Jönköping (SE);
Daniel Britton, Calgary (CA); **Jan Adler**, Skillingaryd (SE); **Wesley Fleming**, Calgary (CA)

(73) Assignee: **Thule Sweden AB**, Hillerstorp (SE)

(**) Term: **15 Years**

(21) Appl. No.: **29/650,876**

(22) Filed: **Jun. 11, 2018**

Related U.S. Application Data

(63) Continuation of application No. 29/609,270, filed on Jun. 29, 2017, now Pat. No. Des. 820,169, which is a continuation of application No. 29/565,473, filed on May 20, 2016, now Pat. No. Des. 793,914.

(57) **CLAIM**

The ornamental design for a stroller, as shown and described.

DESCRIPTION

FIG. 1 is a top front perspective view of a stroller showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of a stroller showing the claimed design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the figures show portions of the stroller that form no part of the claimed design.

1 Claim, 14 Drawing Sheets
